Primary Examiner — Lauren R Calve(74) *Attorney, Agent, or Firm* — Vladimir Vitenberg; James Ernest Oehlenschlager(57) **CLAIM**

The ornamental design for a blister package, as shown and described.

DESCRIPTION

FIG. 1 is a perspective view of a blister package; FIG. 2 is a front view thereof; FIG. 3 is a rear view thereof; FIG. 4 is a left side view thereof; FIG. 5 is a right side view thereof; FIG. 6 is a top plan view thereof; and FIG. 7 is a bottom plan view thereof. FIG. 8 is a perspective view of a blister package according to a second embodiment; FIG. 9 is a front view thereof; FIG. 10 is a rear view thereof; FIG. 11 is a left side view thereof; FIG. 12 is a right side view thereof; FIG. 13 is a top plan view thereof; and FIG. 14 is a bottom plan view thereof. The broken lines do not form any part of the claimed design.

1 Claim, 10 Drawing Sheets(56)
